UNITED STATES PATENT OFFICE

JAMES S. ABERCROMBIE, JOSEPH A. TENNANT, AND HERBERT ALLEN, OF HOUSTON,
TEXAS, ASSIGNEES, BY DIRECT AND MESNE ASSIGNMENTS, TO STEPHENS PUMP
COMPANY, OF ROUND ROCK, TEXAS, A CORPORATION OF DELAWARE

PUMP

Application filed January 15, 1932. Serial No. 586,907.

This invention relates to pumps designed for pumping abrasive and corrosive fluids, of the general type disclosed by Letters Patent of the United States to Charles D. Stephens, 5 #1,832,259 of November 17th, 1931.

This type of pump includes a pumped fluid chamber, inlet and outlet valves therefor, a hollow expansible member within the chamber, and a piston to actuate fluid confined 10 within the member to cause expansion and contraction thereof, whereby fluid is drawn into the chamber through the inlet valve and forced out of the chamber through the outlet valve.

15 The conventional expansible member comprises a rubber tube having an internal annular flange at one end and an external annular flange at the other, the flanges being clamped on the end walls of the chamber.

20 When the flange clamping devices are tightened excessively by unskilled workmen in the field, the flanges are crushed so that the expansible member becomes disconnected from the end walls of the chamber.

25 To prevent this, the present invention has for its object the provision of an expansible member having new and improved means whereby it may be connected to the end walls of the pump chamber.

30 The preferred embodiment of the invention is illustrated by the accompanying drawing of which Fig. 1 is a sectional elevation of a portion of the pump; Fig. 2, a fragmentary external view of the ends of the expansible member; and Fig. 3, a fragmentary sectional view of the ends of the expansible member and the adjacent elements of the pump.

In the drawing, the pump barrel is indicated at 1. It defines a pumped fluid chamber 2, into which fluid is admitted through 40 an inlet valve 3 and from which fluid is permitted to escape through an outlet valve 4. Within the chamber is the expansible member 5. The numeral 6 indicates the piston.

45 When the piston 6 is moved to the left by the rod 7, a portion of the actuating fluid confined within the member 5 is displaced, and the member 5 is thereby expanded to force the pumped fluid out of the chamber 2 through the outlet valve 4, the inlet valve 3

remaining closed. When the piston 6 is moved to the right by the rod 7 the expansible member 5 contracts, outlet valve 4 closes, and inlet valve 3 opens to permit a fresh charge of fluid to enter the chamber 2. This 55 operation is repeated as the piston 6 is reciprocated, fluid being thereby pumped from the inlet pipe 8 through the outlet pipe 9.

The new and improved expansible member provided by this invention has a flexible body 5—a preferably made of rubber. One end of this body is clamped between an external ring 5—b and an internal ring 5—c. The external ring 5—b is L-shaped in cross section and extends inwardly to form an internal annular flange 5—b'.

The other end of the body 5—a is clamped between an external ring 5—d and an internal ring 5—e. The internal ring 5—e is substantially L-shaped in cross section and extends 70 outwardly to form an external annular flange 5—e'.

The flange 5—b' is clamped between the holding element 10 and one end wall 11 of the chamber 2. Suitable gaskets 12 may be 75 placed on either side of the flange 5—b' to seal the parts together.

The flange 5—e' is clamped between the holding element 13 and an internal annular flange 14 in the other end wall of the chamber 80 2. Suitable gaskets 15 may be placed on either side of the flange 5—e' to seal the parts together.

The holding element 10 may be moved toward the adjacent end wall of the cylinder by 85 rotating the element 16 to which it is threaded as indicated at 17; and the holding element 13 may be secured to the barrel by suitable bolts 14.

The rings 5—b, 5—c, 5—d and 5—e are 90 preferably made of some metal, for example steel, that is rigid and capable of resisting relatively great crushing forces, so that the expansible member 5 may be easily mounted in the correct position in the chamber and the 95 flanges 5—b' and 5—e' will not be crushed if the holding elements 10 and 13 are excessively tightened.

We claim:

1. A pump having a chamber; inlet and 100

In testimony whereof, we hereunto affix
our signatures.

JAMES S. ABERCROMBIE.
JOSEPH A. TENNANT.
HERBERT ALLEN.

70

outlet means for said chamber; a pumping member in said chamber and having a tubular, flexible rubber body; inner and outer rigid metallic rings between which one end of said body is clamped, said outer ring being substantially L-shaped in cross section and extending inwardly to form an internal annular flange; inner and outer rigid metallic rings between which the other end of said body is clamped, the inner ring of said latter rings being substantially L-shaped in cross section and extending outwardly to form an external annular flange; said flanges being capable of resisting relatively great crushing forces; means to clamp said flanges to the end walls of said chamber; and means to expand and contract said member to draw fluid into said chamber through said inlet means and to force it out of said chamber through said outlet means.

2. A pump having a chamber; inlet and outlet means for said chamber; a pumping member in said chamber and having a tubular, flexible body, a metallic external flange on one end, and a metallic internal flange on the other end, said flanges being capable of resisting relatively great crushing forces; means to clamp said flanges to the end walls of said chamber; and means to expand and contract said member to draw fluid into said chamber through said inlet means and to force it out of said chamber through said outlet means.

3. A pump having a chamber; inlet and outlet means for said chamber; a pumping member in said chamber, and having a tubular, flexible body, a metallic external flange on one end and a metallic internal flange on the other end, said flanges being rigid; means to clamp said flanges to the end walls of said chamber; and means to expand and contract said member to draw fluid into said chamber through said inlet means and to force it out of said chamber through said outlet means.

4. A pumping member having a tubular, flexible body; inner and outer rings between which one end of said body is clamped, said outer ring being substantially L-shaped in cross section and extending inwardly to form an internal annular flange; and inner and outer rings between which the other end of said body is clamped, the inner ring of said latter rings being substantially L-shaped in cross section and extending outwardly to form an external annular flange; said flanges being capable of resisting relatively great crushing forces.

5. A pumping member having a tubular, flexible rubber body; an external annular metallic flange at one end; and an internal annular metallic flange at the other end; said flanges being capable of resisting relatively great crushing forces.
